(57) **CLAIM**

The ornamental design for a heated hair roller, as shown and described.

DESCRIPTION

FIG. 1 is a front view of the heated hair roller of the invention; FIG. 2 is a back view of the heated hair roller shown in FIG. 1;

FIG. 3 is a first side view of the heated hair roller shown in FIG. 1;

FIG. 4 is a second side view of the heated hair roller shown in FIG. 1;

FIG. 5 is a top view of the heated hair roller shown in FIG. 1; and;

FIG. 6 is a bottom view of the heated hair roller shown in FIG. 1, including environmental structure depicted with broken lines, said broken lines forming no part of the claimed design; and,

FIG. 7 is a front perspective view of the heated hair roller shown in FIG. 1.
